(57) CLAIM

The ornamental design for a canopy for a lounge as shown and described.

DESCRIPTION

FIG. 1 is a perspective view of the canopy for a lounge in accordance with our new design.

FIG. 2 is an elevational view of the canopy for a lounge as seen from the front of FIG. 1.

FIG. 3 is an elevational view of the canopy for a lounge as seen from the back of FIG. 1.

FIG. 4 is an elevational view of the canopy for a lounge as seen from the right side of FIG. 1.

FIG. 5 is a top plan view of the canopy for a lounge; and, FIG. 6 is a bottom plan view of the canopy for a lounge. In the drawings, the broken lines depict environmental subject matter only, and form no part of the claimed design.
